UNITED STATES PATENT OFFICE.

ELIAS ROBERTS, OF CHICAGO, ILLINOIS, ASSIGNOR OF ONE-HALF TO EDWARD BAUMANN AND WILLIAM H. LOTZ, OF SAME PLACE.

GRAIN-ELEVATOR.

SPECIFICATION forming part of Letters Patent No. 256,244, dated April 11, 1882.

Application filed January 31, 1882. (No model.)

To all whom it may concern:

Be it known that I, ELIAS ROBERTS, of Chicago, in the county of Cook and State of Illinois, have invented certain new and useful Improvements in Grain-Elevators; and I do hereby declare that the following is a full, clear, and exact description thereof, reference being had to the accompanying drawings, and to the letters of reference marked thereon, which form a part of this specification.

This invention relates to the construction of the elevator-legs in grain-houses. These legs extend from the boots in the basement or cellar of a grain-house to the uppermost floor of the cupola, and generally consist of rectangular tubes, inside of which the bucket-belts are moving. Such legs are generally framed of boards two inches thick, and are frequently of a length of one hundred and thirty-five feet each, and while they are secured with their bottom ends to the boot of the elevator that sets in a tank between the foundation-piers of the building, the upper extremities of these legs are connected with the box that incases the upper elevator-pulley and carries the delivery-spout, and is called the "elevator-head." The buildings, inside of which these elevator-legs are located in a vertical or slightly inclined position have to be very strong structures placed upon heavy foundations to make them sustain the tremendous weight of the grain stored therein, and the bins, which occupy generally about sixty feet of the entire height of such a building, for the purpose of making them equal to the side pressure of the grain, are generally built of planks spiked flatwise one on top of the other, so as to form solid walls about from four to eight inches thick. These buildings, when first filled with grain, will not only settle until all the frame joints have come to a solid bearing, but all horizontal tiers of timber will shrink to some extent, and the boards that form the bin-walls will shrink together considerably during the first year after the building is erected, and so as to reduce the entire height of the bins from nine inches to one foot, and sometimes more. Now, while the grain-house will thus shrink in height, the elevator-legs will not, and in consequence al-

lowance has to be made for these legs to remain intact and maintain their position while the building will settle, which was heretofore accomplished by sustaining these legs in the structure between timbers forming slip-joints, and after the building had settled as much as could be expected the elevator-legs had to be cut and the elevator-heads lowered proportionally, all of which has been a considerable expense and a tedious job to perform in a good workmanlike manner.

Therefore it is the object of my invention to overcome the above difficulties by an arrangement that will allow the elevator-legs to shorten as the building settles; and it consists of the devices and combinations of devices, as hereinafter described and specifically claimed.

In the accompanying drawings, Figure 1 represents a partial vertical transverse section of a grain-house and of one of the elevators therein; Fig. 2, a sectional plan; Fig. 3, a vertical section, and Fig. 4 an end elevation of that portion of the elevator-legs having my improvements.

Like letters represent corresponding parts in all the figures.

A denotes the lower floor of a grain-house; B, the grain-storage bins, and C D E the three stories of the cupola in which the weighing and spouting of the grain is performed, and F the uppermost floor of the cupola, that contains the machinery for hoisting the grain. A tank, a, for each elevator is located between two foundation-piers, and into this is placed the elevator-boot b, inside of which the lower elevator-pulley, c, is pivoted. The upper elevator-pulley, d, on the top floor of the cupola, is incased by the elevator-head d, having delivery-spout f. The elevator-belt g, carrying buckets h, is stretched over pulleys c and d, and is protected and guided in the elevator-legs i and j, each consisting of a long tubular box rectangular in cross-section. These legs extend from the boot b to the elevator-head e, and were made continuous heretofore.

Just above the bins B, I separate each leg in an upper section, i, and a lower section, j, with a space between twenty to twenty-two inches. These leg-sections i and j, I connect by a box,

k, the inside dimensions of which are equal to the outside dimensions of the elevator-leg. This box *k*, I connect rigid with the sections *j* by wood-screws, and the opposite end of the box *k*, which surrounds the end of a leg, *i*, but is not made rigid therewith, I re-enforce by a frame, *l*. The connection thus made will hold the two leg-sections *i* and *j* in line with each other, and will form a telescoping joint, which will allow these sections to approach each other proportionally as the building is settling.

With this improvement I can secure the sections *i* of each elevator-leg rigid to the floors in the several stories of the cupola, while in the bins, where the principal shrinkage takes place, I sustain the sections *j* between cross-timbers that are loosely jointed with the legs, and thus I can save the trouble and expenses of watching, cutting down, and overhauling the several elevator-legs in a grain-house during and after the period its settling is taking place.

This device of telescoping connections I also apply for a like purpose to all spouts that are

carried more or less vertically through the bins for transferring and shipping grain.

What I claim is—

1. The elevator-legs in grain-elevators, vertically composed of sections *i* and *j*, and connected by sleeves *k*, in which the leg-sections will slide to accommodate themselves to the shrinkage and settling of the building, all substantially as and in the manner described and shown.

2. In a grain-elevator, and in combination therewith, of the elevator-legs composed of the upper sections, *i*, and the lower sections, *j*, both connected by a box or sleeve, *k*, that is made rigid with sections *j* and will form a guide for section *i*, all substantially as and for the purpose described and shown.

In testimony that I claim the foregoing as my invention I affix my signature in presence of two witnesses.

ELIAS ROBERTS.
